HIGH FREQUENCY IMPEDANCE UNIT

Andrew Alford, New York, N. Y., assignor to International Telephone & Radio Manufacturing Corporation, a corporation of Delaware

Application August 3, 1939, Serial No. 288,133

12 Claims. (Cl. 178—44)

My invention relates to high frequency impedance units and more particularly to units designed to operate as substantially pure resistances for dissipation of ultra-high power energy.

In working with ultra-high frequencies, for instance, energy of the order of 125 megacycles, it is often necessary to dissipate a certain amount of the ultra-high power in a resistor or resistors. For example, it is often desirable to terminate a transmission line into its surge impedance for the purpose of making measurements. Also, it is sometimes desirable to terminate a single wire into its surge impedance. Because of these requirements it is very convenient to have pure resistors of various values for purposes of measuring impedance, power, and so forth.

It is generally not very difficult to construct a unit which will produce a certain resistance at a given frequency. However, even these units usually have a variable resistance depending upon the amount of power dissipated in them. For example, a combination of a section of transmission line with a branched section and a lamp or a carbon resistor may be designed to have almost any value of resistance at a particular frequency. However, these units must be adjusted to a different value every time a frequency is changed.

Other known resistors have been produced which have relatively pure resistance, and are therefore useful at a plurality of frequencies. However, such units, generally carbon resistors, must be very small in order that a small reaction may be obtained, and for this reason can dissipate only a small amount of power.

A termination may be furnished by provision of a section of transmission line of sufficient length and attenuation to operate as a load for dissipating the energy. However, any transmission line sufficient to dissipate an appreciable amount of power would have to be quite long and not adapted to provide a unit which may be readily handled.

In my prior Patent No. 2,159,646 issued May 23, 1939, is disclosed a resistance wire artificial line unit suitable for terminating an antenna, or transmission line, and possessing substantially only resistance characteristics.

These units comprise coils of a small diameter but usually many feet long. The number of turns per unit length is adjusted in order to obtain a variation in the resistance. When such coils are made long with respect to their diameter, it is found that they are independent of whether the far end is open or connected to

ground, and the resistance is found to be substantially equal to the surge impedance of the coil considered as a long line. The surge impedance of these units may be calculated with a fair degree of accuracy by assuming the capacity per unit length of the coil is the same as it would be if the coil were a solid bar, and the inductance value may be derived from a known formula for long solenoid coils.

10 With these simple solenoid coils I have experimentally discovered that artificial lines having certain surge impedances in the order of several thousand ohms, may be quite readily constructed. When a lower surge impedance is desired the number of turns per unit length of necessity are reduced to a point where the attenuation per foot of coil is relatively low, so that the coil must be made inconveniently long in order to reduce reflection from the end thereof.

15 20 In accordance with my invention a coil somewhat similar to that described above is utilized. However, the characteristics of the coil are preferably controlled by winding it upon some hollow insulating form and inserting into the hollow a metallic conductor such as a rod or tube. The rod or tube acts as a load on the transmission line and produces a capacity reactance which neutralizes the inductive reaction due to the separation of the turns of the coil and enables the

25 30 35 production of a coil of relatively smaller dimensions, which will operate substantially as a pure resistance unit. Instead of inserting the capacity neutralizing conductor inside the coil, it may be arranged externally and along the length of the coil.

It is an object of my invention to produce an impedance unit which may be utilized as a high resistance termination for ultra-high frequency systems.

40 45 According to another feature of my invention, the surge impedance of the structure may be varied by changing the pitch of the coil and it is a further object of my invention to provide a resistance unit which may be made variable by means for changing the pitch of the coil.

According to another feature of my invention, the effective resistance of the unit may be varied by changing the capacity effect of the inner conductive member.

50 It is, therefore, a still further object of my invention to provide an impedance unit in which the effective surge impedance may be changed by an adjustment of the capacity effect of the conductive member.

Furthermore, the unit may be made of a con-

ductor with tapered resistance characteristics, so that a more uniform dissipation of energy along the unit will occur.

Other features and objects of my invention will be apparent from the particular description thereof, made in connection with the accompanying drawings, in which—

Fig. 1 is a diagrammatic showing for the purpose of illustrating the principles of my invention,

Fig. 2 is a diagrammatic showing of a preferred embodiment of my invention for terminating a two conductor transmission line;

Figs. 3 and 3A are illustrations of embodiments of my invention wherein the pitch of the solenoid coil is made adjustable;

Fig. 4 is a fragmentary view of a portion of an impedance unit in accordance with my invention, wherein the central conductor unit is adjusted for changing the effective resistance;

Figs. 5, 5A and 6 are further embodiments of my invention illustrating other arrangements for varying the effective diameter of the central conductive member, and

Fig. 7 illustrates a central conductor core of tapered form.

In my prior Patent No. 2,159,646, it is shown that an artificial line comprising a long solenoid made of resistance wire in which the diameter of the solenoid is small in comparison with the length of the solenoid, and the pitch between the wire units is made in the order of magnitude of the solenoid diameter, will offer high attenuation per unit length to high frequency energy. Such an artificial line serves to attenuate the energy transmitted along it so that at the remote end a small amount of energy is reflected. The reflected energy is also attenuated upon its return, so that by making the coil of sufficient length the energy is substantially all dissipated in the artificial line. Thus the arrangement provides a termination which acts substantially as a pure resistance unit for terminating a transmission line or antenna conductor. This type of arrangement, however, is not convenient for use where low impedances are required, because in order to prevent reflections such coils become unduly long.

In accordance with my invention, this difficulty is overcome by providing coils similar in structure to those above described except that the pitch between turns may be reduced, and adjacent the coil and extending substantially along the length thereof is provided a metallic conducting member which serves to load the artificial line and reduce the impedance per unit length, without widening the pitch of the coils.

The principle of a system in accordance with my invention will be more fully explained in connection with Fig. 1 in which at 10, is shown a source of high frequency energy, this source of energy is preferably one having a frequency in the ultra-high frequency range, that is above six megacycles. One side of high frequency source 10 is connected to element 11, which may be a metal plate or trough, a concentric shell around these units, or ground. The output side of the high frequency source is connected to a terminal T of a coil of wire 12 preferably of high resistance. This coil may be made of any suitable material having high resistance, for example, of stainless steel. Coil 12 is wound on a hollow cylinder 13, made of insulating material such as glass. The length of the coil is made long relative to the diameter thereof, that is at least as long as the coil diameter, and preferably at least

several times this length. The length of the wire forming the coil is made electrically long, at least a half wavelength and is preferably more than a wavelength long at the operating frequency, and the pitch of the coil winding is made to furnish the desired length of wire to provide the desired attenuation per unit length of the work.

Energy from source 10 traverses coil 12 and is highly attenuated as it advances toward the open end of the coil. The energy which reaches the terminal open end of the solenoid 12 is then reflected and is further attenuated as it travels back along the conductor. By making the coil of sufficient length substantially complete attenuation of the energy is attained, so that the impedance unit operates as though it were a substantially pure resistance to dissipate substantially all of the energy.

The effectiveness of this coil in dissipating energy may be considerably improved by providing a conductive element extending along the coil adjacent the coil turns, such as conductor element 14, in the form of a rod or a tube inside tube 13. When this tube or rod 14 is adjusted so that its end is spaced substantially in the plane of the first coil of solenoid 12, the unit will act as substantially a pure resistance unit having a lower surge impedance than the coil, without the inserted member. By using a conducting member adjacent the coil turns, the surge impedance of the unit may be reduced in the order to two to one. Variation in the diameter or rod 14 serves also to change the total resistance effect of the unit. Thus, if the rod is made of a larger diameter it will serve to more completely neutralize the inductive impedance of the solenoid 12 and will reduce the surge impedance of the unit considerably. The smaller rods will have less effect and will reduce the impedance to a lesser extent.

By translating the rod 14 a short distance, it is possible to make the impedance either partially capacitive, a pure resistance, or partially inductive. By displacing rod 14 to the left so that it extends slightly beyond the end of solenoid 12, the unit is made partially capacitive. When the rod is adjusted so that its end terminates substantially even with the end of the coil, the unit is substantially a pure resistance, and when the end of rod 14 is to the right of the last turn, the unit becomes partially inductive. This adjustment may be useful for the purpose of compensating for a small capacity or inductance caused by the terminals connecting the unit to the ends of the transmission lines or leads.

The effectiveness of the conductor element may be explained as follows: When the coil is used alone the capacity for neutralizing inductive effects must be obtained by the capacity of the turns themselves to ground or to an effective neutral surface. Accordingly, the coil must be made sufficiently long to provide the needed capacity. By using a conductive means adjacent the coils a relatively large capacity between the turns and the conductive means is effected. These separate capacities are connected together effectively by the conductive means so that a resultant total capacity to ground or the neutral surface of the coil becomes that of the conductor means. Since the coil conductor is electrically long the current amplitude will differ widely at different points thereon so that capacity reactances of neutralizing nature will occur, these being connected together by the con-

ductive means. The closer the conductive means is to the wire forming the coil the larger will be the capacity and the lower the surge impedance of the coil. Accordingly, if a relatively short coil is used the insulation between the coil turns and the conductive means must be very thin. Preferably, the coil is made small in diameter, for example, in the order of 1" or less in diameter.

While I have shown in Fig. 1 an arrangement whereby the capacity neutralizing conductor is placed within the coil, it is to be understood that a similar effect may be achieved by conductors external of said coil. For example, a concentric metallic tube may be arranged outside the coil. However, the internal arrangement is preferable as it provides a more compact unit. Furthermore, considerable energy is dissipated in the coil and as a consequence a large amount of heat is produced. Cooling of the unit may be more readily achieved if it is not closely surrounded externally with a metallic covering.

Since as pointed out above considerable heat is dissipated from the unit, it is clear that if the coil conductor is made to have a uniform resistance or attenuation effect per unit length, the end thereof connected to the high frequency terminal will become heated to a higher temperature than the remote end. In order to minimize this effect the unit may be constructed so as to have different attenuation factors along the length thereof. Such tapered attenuation characteristics may be achieved by varying the pitch of the coil, that is, by providing a wider pitch near the terminal end to give reduced attenuation per unit length, and a smaller pitch toward the open end to produce greater attenuation per unit length.

The result may also be achieved by using a wire with tapered resistance characteristics. Such a wire may be actually made tapered, but a more practical solution resides in the provision of a wire of resistance material coated with a thin plating of conducting material. For example, an iron wire may be drawn through an electro-plating bath, and as the wire is advanced the electro-plating voltage may be reduced so as to deposit a coating of continuously reduced thickness on the wire. An approximation of a tapered wire effect may be achieved by connecting serially wires of different resistance characteristics, or two separate units with different attenuation characteristics may be serially connected as a line termination.

The impedance unit may be utilized for various purposes wherein a large terminal resistance is desired. For example, the unit may be used for terminating a single wire such as an antenna into its surge impedance so as to produce only traveling waves therein. Furthermore, a pair of these units may be provided for terminating a two conductor transmission line into its surge impedance. In Fig. 2 is illustrated a structural embodiment of my invention in a double unit for use in terminating a two conductor line. The transmission line conductors 21 are shown connected to terminals 22, 23, respectively. These terminals serve to connect the conductors 20, 21 with the high resistance coil wires 24, 25. The wires 24, 25, are wound on insulating cores 26, 27 and centrally disposed with respect to these cores are provided tubular conductors 28, 29. These resistance wire units and cores are enclosed in housing members 30, 31, respectively, for protecting them from the atmosphere. These housing members may be made of metal or of insulat-

ing material as desired and are preferably provided with ventilating perforations 34. When the unit is utilized for a combination of a transmission line, the metal housing is preferable. However, when a unit is provided for terminating an antenna, it is preferable to make the housing of insulating material. For use in terminating a two conductor line, the two units may be firmly attached together by any suitable clamping means. The insulating tubular member 28 is supported within housing 30 by means of insulating discs 35, 36. Tube 28 is slidable through an opening provided in disc 36 so that it may be adjusted to compensate for capacitive or inductive effects of terminal 22 and is slidably supported at its other end by a rod of insulating material 37 extending through a perforation in disc 35. The tube 28 is threaded through an insulating washer 32, and is provided with a knurled head 33 for adjusting the position of rod 28, relative to the terminal end of the coil formed by wire 24.

Although disc 32 is described as being made of insulating material, it is clear that when tube cover 30 is made of insulating material, the disc 32 may be made of any desired material, whether insulating or conductive.

In Fig. 2 is illustrated two of these impedance units fastened together, it is clear, however, that a single unit housed as illustrated in this figure may be used if desired.

In an actual construction of a two element unit in accordance with my invention, two supporting tubes of one-half inch Pyrex glass tubing about thirty-six inches long were used. On each of these tubes was wound a coil of No. 36 B & S gage wire with a pitch of 12 turns per inch, the coil being 35½ inches long and having approximately 400 ohms direct current resistance. The glass tubes were supported slidably on pins of insulating material and spaced apart by means of a supporting bracket. The tube supporting pins were turned down at their inner ends and fitted into a $\frac{1}{8}$ inch copper tube, holding this tube centered within the Pyrex glass tube. Relative adjustment of the coil and copper tube was achieved by sliding the glass tubes on the supporting pins. The supporting bracket was constructed to permit adjustment of the spacing between the two glass tubes. Instead of separate shields as shown in Fig. 2, the unit was mounted in a single ventilated shielding box 2½ inches square and approximately 39 inches long. With a given adjustment of the spacing the reactance of the unit was adjusted by moving the glass tubes as outlined above. The unit so constructed presented approximately 600 ohms resistance and was capable of dissipating about 100 watts.

In Fig. 3 is illustrated an arrangement provided for varying the pitch of the wires used in forming the solenoid. Wire 24 is clamped to tube 26 at one end by means of a clamping disc 40 which also serves as a support for one end of tubes 26 and 28. The other end of the conductor 24 is fastened to a ring 41 slidably mounted on insulating tube 26. A number of rods 42 are securely fastened at one end to ring 41 and slidably pass through supporting ring 36 and covering disc 32. On the outer end of rods 42 are provided nuts 43 for adjusting the position of the rods and consequently discs 41 relative to the longitudinal dimension of tube 26. Conductor 24 is made of resilient material so as to act somewhat in the manner of a coil spring. By tightening nuts 43 the coil formed by conductor 24 may

be extended so as to increase the pitch between the individual conductor turns. Similarly, by loosening these nuts 43, the turns of the coil formed by conductor 24 are permitted to retract toward each other so as to reduce the pitch.

Although in Fig. 3 the solenoid has been illustrated so as to operate as a tension spring, that is, so as to tend to close up, it is clear that the solenoid may be wound to operate as a compression spring. In this case, means must be provided on rods 42 to prevent the coil from extending when it is desired to compress it. This may be accomplished by any known arrangement, for example, may be provided internally of closure member 32 for this purpose.

Because of the tendency of the wire to stick, the arrangement of Fig. 3 may not be satisfactory for maintaining a uniform conductor spacing upon change in pitch. This difficulty may be overcome by making insulating tube 26 of some resilient material such as rubber and providing spiral holding grooves such as shown at 45 in Fig. 3A. Instead of then extending the wire as shown in Fig. 3, the insulating core may be stretched and because of the grooves the wire will be correspondingly moved to vary the pitch. Instead of grooves, the core may be provided with raised portions or ridges to hold the wire in spaced relation.

As pointed out above, the resistive effect of the impedance unit may be varied by changing a dimension of the centrally located conductor. In Fig. 4, a fragmentary view of an embodiment of my impedance unit permitting continuous variation of the effect of the central conductor is illustrated. In this figure, the central conductor member 28 instead of being a single continuous conductor is made up of a plurality of conductive discs 50 mounted in contact with a central rod 52 and separated by resilient washers 51. These washers may be made of rubber or similar resilient material, or may be replaced by coiled springs if desired. Although discs 50 are separated from each other somewhat by the insulating material, still the conductive rod will operate substantially as a continuous conductor. Centrally disposed with respect to discs 50 and washers 51, is provided a rod 52, one end of which is provided with a head 53 to permanently hold discs 50 in place at the end thereof. The other end of rod 52 is threaded and a nut 54 which may be turned by means of a knurled head as shown, is provided. By adjusting the position of nut 52 the spacing between conductive discs 50 may be varied and thus the capacity effect of the unit may be changed. These discs and washer unit should extend beyond the open end of coil 24 so that compression or expansion of the resilient members will serve only to change the effective density of the conductor and not alter the effective position of the unit as a whole with respect to the coil. By compressing these members so as to bring the discs closer together, the same effect is obtained as though the rod were increased in diameter, that is, the effective capacity is increased and consequently the total resistance effect of the units is lowered. By constructing the impedance units in this manner, a continuous adjustable resistance between desired ranges may be obtained.

In Fig. 5 is illustrated another form of central conductor unit for providing an adjustable resistance effect. In this arrangement the conductor unit 28 is made of a split conductor tube 60. Tube 60 may be of resilient material so as

to tend to close together. In each end of tube 60 are provided tapered blocks 61, 62 having a diameter at their smaller ends such as to fit into the ends of the tube, and a larger diameter greater than that of the tube. Centrally disposed within member 28 I provide a rod 66, which passes through block 62 and may be threaded at one end and adjusted in position by means of a nut 67. At the other end said rod is attached to block 61. Upon tightening of nut 67 blocks 61 and 62 are brought toward each other to spread apart tube 60 so as to increase its effective diameter. Conversely upon loosening nut 67, blocks 61 and 62 are separated by compression of tube 60, reducing the effective diameter of the tube. It is thus clear that an arrangement of this kind also provides a system wherein the effective resistance of the impedance unit may be continuously varied between such desired limits.

Another embodiment may be provided wherein the internal tube 28 is made in two semi-cylindrical sections which may be relatively rotated as shown in Fig. 6. In this figure, 28 is made of sections 70 and 71. Section 70 is provided with supporting discs 72 and is tapered at one edge substantially to a point. Section 71 is rotatably mounted within section 70 and is fastened to a disc 73. The disc is provided with a turning handle 74 so that more of section 71 may be exposed adjacent the coil windings to increase the capacity effect. This embodiment does not have uniform capacitive effect about the entire coil periphery but does provide an adjustable capacity to vary the overall resistive effect.

The core element 28 may also be made in tapered form if desired, as indicated in Fig. 7. This core shape produces a different capacity effect along the coil and so in effect produces a tapered impedance characteristic. For this reason it is clear that the tapered core may be used in place of the tapered winding, as described above.

Numerous other arrangements for varying the adjustment of the tube sections or coil windings may be readily provided by those skilled in the art to accomplish the desired results.

A number of impedance units utilizing the principles outlined above have been constructed. In these units the ratio of diameter of coil to the length thereof has generally been in the order of $\frac{1}{20}$ or more. In one example utilizing frequencies in the order of 125 megacycles, an arrangement was utilized wherein resistance wire was wound upon a glass tube $\frac{1}{8}$ of an inch in diameter. A copper tube $\frac{1}{8}$ of an inch in diameter was inserted into the glass tube. The number of turns of wire on the glass tube per centimeter was eight. With this unit as constructed the surge impedance is substantially 450 ohms. The attenuation along the coil was so high that the line need be only 18 inches long in order that the unit will act as a substantially pure resistor.

Although in the preferred arrangement the coil is made of resistance wire, to provide the desired attenuation effect it is clear that the attenuation may be secured in the central conductor member if desired. This may be accomplished in a number of different ways. For example, with a central conductor formed as a split cylinder as shown in Fig. 5, a plurality of high resistance wires 90 may be connected across the gap forming the split so that a high resistance around the tube occurs while the longitudinal resistance is maintained low as shown in Fig. 5A.

Various other means for providing high losses in the core while preserving the longitudinal conductance thereof may be provided within the knowledge of those skilled in the art.

When high resistance cores for producing the losses are provided, the coil may be made of good conducting material. A combination of these effects may be used if desired, so that part of the attenuation occurs in the coil and part in the conductor, the essential feature residing in the provision of means of sufficient length and attenuation so that substantially all of the energy is dissipated in the network.

While I have disclosed a few of the preferred embodiments of my invention, it is to be distinctly understood that this description is made only by way of illustration. What I consider my invention and upon which I desire to secure protection is embodied in the accompanying claims.

What I claim is:

1. An impedance unit for high frequency energy comprising a wire coil means, said coil means being long relative to its diameter, and the length of the wire forming said coil being at least one wavelength at the operating frequency, a connecting terminal at one end of said coil constituting the sole means for connecting said unit to external circuits, and a conductive means mounted adjacent said coil extending along the length thereof and insulated therefrom, one end of said conductive means terminating at a point adjacent the terminal end of said coil and at least one of said means being made by resistance material.

2. An impedance unit according to claim 1, wherein said wire is made of high resistance material, and said conductive means of low resistance material.

3. An impedance unit according to claim 1, wherein said conductive means provides a good conductance longitudinally of said coil, and a high resistance transversely of said coil.

4. An impedance unit for high frequency energy comprising a hollow cylinder of insulating material, a coil of resistance wire wound on said hollow cylinder, the diameter of said coil being small with respect to the length thereof and the length of said wire being at least one wavelength at the operating frequency, means for reducing the inherent surge impedance of said coil comprising a conductive rod inserted within said cylinder, said rod terminating at a point adjacent one end of said coil, a connecting terminal on one end of said coil, said terminal being the sole means for connecting said impedance unit to external circuits.

5. An impedance unit according to claim 4, wherein said resistance wire has a tapered resistance characteristic with its minimum resistance end forming said terminal end of said coil.

6. An impedance unit for high frequency energy comprising a hollow cylinder of insulating material, a coil of resistance wire wound on said hollow cylinder, the diameter of said coil being small with respect to the length thereof and the length of said wire being at least a wavelength at the operating frequency, means for reducing the inherent surge impedance of said coil comprising a conductive rod inserted within said cylinder, said rod terminating at a point adjacent one end of said coil, and means for adjusting the relative position of said coil and said rod between a position where said rod extends slightly past said end of said coil and a position where said rod end is slightly short of said end

of said coil to alter said impedance unit from slightly capacitive reactive to slightly inductively reactive.

7. An impedance unit according to claim 6, further comprising means for variably adjusting the resistive effect of said impedance unit.

8. An impedance unit for high frequency energy comprising a hollow cylinder of insulating material, a coil of high resistance wire wound on said hollow cylinder, the diameter of said coil being less than $\frac{1}{3}$ the length thereof and the length of said wire being at least a wavelength at the operating frequency, means for reducing the inherent surge impedance of said coil comprising a conductive rod inserted within said cylinder, said rod terminating at a point adjacent one end of said coil, and means for varying the relative effect of said rod and said coil to adjust the impedance of said unit.

9. A high frequency system comprising a conductor of high frequency energy and means for terminating said conductor in its surge impedance comprising a coil of high resistance wire, said coil being long relative to its diameter and the length of said wire being at least a wavelength at the operating frequency, a connecting terminal at one end of said coil connected to said conductor, the opposite end of said coil being unconnected and a conductive means mounted within said coil and insulated therefrom, one end of said conductive means terminating at a point adjacent the terminal end of said coil.

10. A high resistance terminating unit for high frequency conductors, comprising an artificial transmission line formed of a high resistance conductor wound into a coil of a diameter which is small compared to its length and provided at but one end with a connecting terminal, the length of said conductor being at least a wavelength at the operating frequency, and conductive means adjacent said coil turns forming a distributed capacity loading for said artificial line, the resistance characteristic of said wire, the diameter of said coil, the pitch of said coil windings and the amount of capacity loading being proportioned to produce the desired load impedance.

11. In a transmission line, a high resistance terminal impedance unit designed to operate as substantially pure resistance for the dissipation of ultra-high frequency energy comprising a wire coil means, said coil means being long relative to its diameter, the length of the wire forming said coil being at least one wavelength at the operating frequency, a connecting terminal at but one end of said wire, connected to said line, the opposite end of said wire being unconnected, a conductive means mounted adjacent said coil extending along the length thereof and insulated therefrom, one end of said conductive means terminating at a point adjacent the terminal end of said coil and at least one of said means being made of resistance material, the arrangement being such that the wire offers high attenuation to high frequency energy transmitted along it and that any energy reflected from the remote end thereof is dissipated, said conductive means being effective to control the total resistance effect of said unit.

12. In a transmission line, a high resistance terminal impedance unit designed to operate as substantially pure resistance for the dissipation of ultra-high frequency energy comprising a coil of resistance wire wound on a hollow cylinder of resistance material, the length of the wire form-

ing said coil being at least one wave length at the operating frequency, a connection for connecting but one terminal of said coil to said transmission line, means for reducing the inherent surge impedance of said coil comprising a conductive rod inserted within said cylinder, said rod terminating at a point adjacent one end of

5 said coil, the arrangement being such that the coil offers high attenuation to high frequency energy transmitted along it and that any energy reflected from the unconnected end thereof is dissipated by the resistance of the coil.

ANDREW ALFORD.
